UNITED STATES PATENT OFFICE.

GEORGE A. WOODMAN, OF CHICAGO, ILLINOIS.

JOURNAL BOX.

Application filed May 31, 1924. Serial No. 716,847.

To all whom it may concern:

Be it known that I, GEORGE A. WOODMAN, a citizen of the United States, residing at Chicago, in the county of Cook and State 5 of Illinois, have invented certain new and useful Improvements in Journal Boxes, of which the following is a specification.

This invention relates to journal boxes for use on passenger cars, locomotives, freight 10 cars or other type of vehicles, and more particularly to the type of journal box known as the pedestal type.

In this type of journal box it has been customary to provide vertical guideways to 15 engage the pedestals of the trucks so as to permit a certain amount of up and down movement between the pedestals and the journal boxes, to provide easier riding. Of course, this up and down movement causes 20 wear in both pedestal and box and in the past various ways have been devised to decrease this wear.

One of the methods used to decrease the wear has been to make the guideways of 25 hard metal inserts. Another method has been to provide the guideways with removable liners attached to the journal boxes so that when these liners are worn out they may be removed and new ones applied. However, 30 neither of these methods has been very satisfactory because, when the hard metal inserts are used it is only a question of time before they will be worn out, and then the box will have to be replaced. When the 35 removable liners are employed these are soon worn out and then the trucks must be removed from under the car while new liners are put in place. Of course, the wear on the pedestals continues in spite of either 40 of the above methods of solving the problem. Any such method as outlined above is objectionable because it calls for taking the car or locomotive out of service and the material and labor necessary to remove the 45 trucks from under the car, replace the journal boxes or liners, and replace the truck under the car is great.

The primary object of my invention is to provide a journal box, particularly one for 50 use with the pedestal type of truck, which will be self lubricating, thereby avoiding all necessity for special inserts or liners, and providing a journal box which will greatly outwear any now known.

55 Another object of my invention is to provide a self lubricating journal box which

may be easily made without any complicated or inexpensive change in the present form of journal box. In other words, my invention may be embodied in a journal box of well-known construction, without materially increasing the cost of making the same.

In the drawings forming a part of the specification in which I have shown a preferred embodiment of my invention,

Fig. 1 is an elevation of a portion of a truck of the pedestal type.

Fig. 2 is a side elevation of a journal box embodying my invention.

Fig. 3 is a view, partly in plan and 70 partly in horizontal section, of my improved journal box.

Fig. 4 is a view, partly in end elevation and partly in cross section, of my improved journal box.

Referring now to the drawings, my improved journal box is designated generally by the numeral 1 and is shown in Fig. 1 supporting a pedestal 2 of a truck 3 of well-known type. The pedestal comprises 80 members 2' which are designed to slide within the guideways 3 of the journal box 1, as is well-known in the art.

The journal box is provided with a front 4, having an opening closed by a cover 5. The guideways 3 are formed in the sides 6 and 7 respectively.

Intermediate the ends of the sides 6 and 7 there are provided inside lugs 8 which act as stops for the journal bearings and 90 wedges, as is well-known in the art. It is common to make journal boxes of malleable cast iron, and in order to eliminate shrinkage cracks in the castings, due to unequal thickness of the walls, the sides 6 and 7 are usually recessed at the lugs 8 so as to 95 maintain the thickness of the sides constant. The result is the recesses 9 which form a three-walled pocket in the sides 6 and 7. The guideways 3 are formed on 100 either side of these pockets by projecting flanges 10.

I make use of the recesses 9 for oil pockets or wells, completing them by casting integrally with the sides 6 and 7 a fourth 105 wall 11, and this oil pocket I pack with waste saturated with lubricating oil. It will be noted that the walls 11 project slightly from the sides 6 and 7 to provide sides 11' to co-operate with the projecting flanges 110 to form the guideways 3.

To permit the oil from the pocket 9 to

reach the guideways 3 I provide openings 12 in the portions 11' through which the oil may flow to the guideways and into grooves 13 provided in the faces of the 5 guideways. These grooves may be omitted, if desired, but in practice I have found that they are satisfactory as a means to enable the oil to readily spread out over the entire width of the guideways and effectively 10 lubricate the wearing surface of both the journal box and pedestal during the up and down movement of the truck. These grooves are shallow and I have shown them arranged in a zigzag fashion and arranged 15 both above and below the openings 12 so that oil may work both ways with the up and down movement of the pedestal. However, any other form or arrangement of grooves may be employed, or they may be 20 omitted altogether, if desired.

From the above it will be seen that I have provided an efficient means for lubricating the wearing surface between the journal box and a truck mounted thereon, and 25 while I have referred to a pedestal truck, I do not desire to be limited thereto, as I contemplate the use of my invention with any type of truck where it is applicable. It will be seen that my improved journal 30 box may be made from a single casting by a modification of a standard journal box, which modification may be easily and inexpensively made. The result is a self lubricating journal box which has been found, 35 in actual practice, to avoid any substantial wear upon either journal box or truck, and which has been found to be most efficient

in operation, avoiding troublesome replacing of journal boxes or liners.

I am aware that changes in the form, 40 construction and arrangement of parts may be made without departing from the spirit and without sacrificing the advantages of the invention and I reserve the right to make all such changes as fairly fall within the 45 scope of the following claims.

I claim:—

1. A journal box comprising a stop for the bearing formed by a recess in the side of said box, and a wall closing said recess 50 to form an oil pocket.

2. A journal box comprising a guideway, a stop for the bearing therein formed by a recess in a side of said journal box, and a wall closing said recess to form an oil 55 pocket, said pocket having an opening communicating with said guideway.

3. A journal box comprising a guideway, a stop for the bearing therein formed by a recess in a side of said journal box, a wall 60 closing said recess to form an oil pocket, said pocket having an opening communicating with said guideway, and means in said guideway for spreading the oil over the surface of said guideway.

4. A journal box comprising a guideway, a stop for the bearing therein formed by a recess in a side of said journal box, a wall closing said recess to form an oil pocket, 70 said pocket having an opening communicating with said guideway, and grooves in the surface of said guideway.

GEORGE A. WOODMAN.
